DESIGN FOR A HOUSE

George W. Walker, Pleasant Ridge, Mich., assignor to Bohn Aluminum & Brass Corporation, Detroit, Mich., a corporation

Application September 1, 1943, Serial No. 111,046

Term of patent 3½ years

(Cl. D13—1)

To all whom it may concern:

Be it known that George W. Walker, a citizen of the United States of America, residing at Pleasant Ridge, in the county of Oakland and State of Michigan, has invented a certain new, original, and ornamental Design for a House, of which the following is a specification, reference being had to the accompanying drawing, forming a part thereof, wherein:

Fig. 1 is a perspective view of a house embodying my design;

Fig. 2 is an elevational view of one end thereof;

Fig. 3 is an elevational view of one side thereof;

Fig. 4 is an elevational view of the opposite side thereof; and

Fig. 5 is an elevational view of the other end thereof.

I claim:

The ornamental design for a house, substantially as shown.

GEORGE W. WALKER.
